UNITED STATES PATENT OFFICE.

WILLIAM HENRY GIBBS, OF HONESDALE, PENNSYLVANIA.

DESIGN FOR A CUT-GLASS VESSEL.

SPECIFICATION forming part of Design No. 31,781, dated November 7, 1899.

Application filed September 27, 1899. Serial No. 731,985. Term of patent 3½ years.

To all whom it may concern:

Be it known that I, WILLIAM HENRY GIBBS, a citizen of the United States, residing at Honesdale, county of Wayne, and State of Pennsylvania, have invented and produced a new and original Design for Cut-Glass Vessels, of which the following is a specification.

The accompanying drawings illustrate my design.

Figure 1 is a plan view of a cut-glass vessel embodying my design, while Fig. 2 is a sectional view of the vessel.

My design consists of a cut-glass vessel having as its leading feature a knob or circular figure A, provided with the circular border of half-diamond cuttings or faces. Within

the circle of half-diamond cuttings is the ornamental figure C.

My design has as a supplemental feature a group or plurality of the essential figures A, located outside and bordering the ornamental field C, and one of said essential figures located at the center of the field.

I claim—

The design for a cut-glass vessel, as herein shown and described.

In testimony whereof I affix my signature in presence of two witnesses.

WILLIAM HENRY GIBBS.

Witnesses:

F. G. FARNHAM,
ROBT. A. SMITH.
